Conn., a corporation of Delaware

Application January 30, 1945, Serial No. 575,341

2 Claims. (Cl. 230—56)

1

This invention relates to a starting system for power plants including a number of free-piston units.

In a power plant of this type the controls may be located at a point remote from the units. A feature of this invention is an arrangement by which the starting of any one of the units may be controlled from a control station. Another feature is a single control by which any one of the units may be started selectively.

If the power plant is used in aircraft, the weight of the power plant should be kept at a minimum. A feature of this invention is an electrical control for the starting systems of the units which will permit the elimination of separate hydraulic or pneumatic lines from each of the units to the control station.

A feature of this invention is a selector by which the operator may determine which unit is to be started, the selector being so arranged that the starting system for each unit may continue to function automatically until the unit is running.

The copending application of Meitzler, Serial No. 550,894 (Patent No. 2,469,739 of May 10, 1949), described a starting system in which the free-piston unit may be started automatically by admitting fluid under pressure to the starting system. In some installations, it may be undesirable to have the starting systems for all of the units operating simultaneously. A feature of this invention is a control by which the several units may be started successively and by which any unit may be started if it stalls.

Other objects and advantages will be apparent from the specification and claims, and from the accompanying drawings which illustrate an embodiment of the invention.

Fig. 1 is a side elevation of the power plant.

Fig. 2 is a sectional view through the compressor with the starting device in elevation.

Fig. 3 is a sectional view of the starting device and the release valve.

Fig. 4 is a sectional view of the cranking device and the supply valve.

Fig. 5 is a diagrammatic view of the entire starting system for the units.

The power plant may include a number of free-piston units 2 acting as gas generators and delivering gas to an exhaust collector 4. The exhaust collector may be surrounded by a scavenging collector 6 for the compressed gas from the unit which is used in scavenging the engine cylinder. A burner 71 which may be located within the exhaust collector is connected to a turbine 8 which

2

drives a propeller system, not shown, on a shaft 9. The units are arranged in groups around the gas collector and operate independently of one another.

5 The unit shown includes an engine cylinder 10 having reciprocating pistons 12 and 14 to which compressor pistons 16 and 18 in cylinders 28 and 22 are integrally connected. Sleeves 24 and 26 attached to the compressor pistons complete the 10 reciprocating piston assemblies. The sleeves reciprocate over stationary pistons 28 and 30 and form air spring cylinders.

The piston assemblies are moved apart by the burning of fuel injected into engine cylinder 10 15 through one or more nozzles 32. Air compressed in the air spring cylinders on the power stroke returns the piston assemblies. The assemblies are always maintained at equal distances from the center of the engine cylinder by a linkage, 20 which may include racks 34 and 36, Fig. 4, projecting from the piston assemblies and meshing with a pinion 38 on a shaft 40.

Intake manifold 42 conducts air to intake valves 44 in the heads of the compressor cylinders 25 through which air alternately enters opposite ends of the compressor cylinders. The compressed air leaves the cylinders through discharge valves 46, also at opposite ends of the compressor cylinders and passes into a central scavenge chamber 48 and end chambers 50 and 52. These chambers may be interconnected by a scavenge manifold, not shown. Compressed gas from the chambers enters engine ports 54 and 56 which are uncovered by pistons 12 and 14 at the end of 30 the power stroke, thereby permitting air to be blown through the engine cylinder. Gas and air in the engine cylinders is discharged through exhaust ports 58 into exhaust manifold 60.

Starting devices 62 for the unit are mounted 35 in the air spring pistons 28 and 30. The devices are similar and only one device will be described in detail. Piston 30 forms a housing having an accumulator chamber 63 in which gas under pressure is collected in readiness for starting. This 40 chamber communicates with the air spring cylinder through a port 64 closed by a poppet valve 66. The stem 68 of this valve is slidable in a guide 70 on a cap 72 which closes the end of chamber 62. Valve 66 closes port 64 by movement toward the storage chamber and is opened by movement away from the chamber so that pressure of gas within the chamber opens the valve. Pressure of gas in the air spring tends to hold the valve closed during operation of the unit. 45 Cap 72 has a bore forming a cylinder 74 which

receives a piston 76 on the end of valve stem 88. The inner end of cylinder 74 is connected with the storage chamber by one or more ports 78. A coil spring 80 in the cylinder moves the piston toward valve closing position. A head 82 closes the outer end of cylinder 74 and is held in position by studs 84 extending through both head 82 and cap 72.

A casing 86 on head 82 has a bore 88 in which a plunger 90 is slidable. One end of bore 88 is closed by head 82, the other end by a cover plate 92. Gas under pressure is admitted to the inner end of bore 88 through a channel 94 in casing 86. With plunger 90 in the position shown, gas entering the inner end of the bore 88 through channel 94 is guided into chamber 63 through a small passage 96 extending between bore 88 and a passage 98 in casing 86, cap 82, and head 72, and the head of piston 30.

Passage 98 intersects bore 88 in alignment with another passage 99 which communicates with the outer end of cylinder 74. Plunger 90 is normally in a position to cut off fluid connection between passages 98 and 99, and has a groove 100, which, when the plunger is moved to the opposite end of its stroke, connects these passages and permits gas to flow through channel 99 into the outer end of cylinder 74, to cause valve 66 to open.

For moving plunger 90 to the inner end of its stroke, casing 86 has a gas inlet passage 102 which is connected by a groove 103 in plate 92 to the outer end of bore 88. When gas under pressure enters this inlet passage, it moves plunger 90 to the left into a position to cover the end of passage 96 and to connect passages 98 and 99 by means of groove 100 to establish fluid connection between chamber 63 and the outer end of cylinder 74. When this occurs, the pressures on opposite sides of piston 76 are balanced and the pressure on valve 66 opens the valve for the escape of gas into the air spring.

In starting the unit, gas under pressure is first admitted through channel 94 until a predetermined pressure is built up in chamber 63. After this pressure is reached, gas under pressure is admitted through passage 102 thereby moving plunger 90 to close passage 96 and to cause valve 66 to open. Before this action occurs, the piston assemblies of the unit will have been moved to starting position. The sudden inrush of air into the air springs from chambers 63 in starting devices 56 and 58 will move the piston assemblies rapidly toward each other.

The starting devices 62 may be controlled by an automatically operating release valve 104 which controls the admission of gas under pressure to channel 94 and passage 102. Valve 104 includes a casing 106 having a bore in which a valve plunger 108 is mounted, the plunger being normally held in the position shown by a spring 110. The tension of spring 110 may be adjusted by a nut 112 engaging threads in casing 106 to control the pressure in chamber 63 at which the starting device operates.

Casing 106 has an inlet port 114 connected to a source of gas under pressure, and an outlet port 116 connected by a conduit 118 to channel 94. Another outlet port 120 spaced from port 116 is connected by a conduit 122 to passage 102. In the normal position of plunger 108 a groove 124 in the plunger connects ports 114 and 116 and another groove 126 establishes fluid connection from port 120 to a chamber 127 at the end of casing 106. When plunger 108 is shifted

to the other end of the stroke, as limited by a threaded ring 128, groove 124 connects inlet port 114 with port 120, and another groove 130 connects port 116 to a vent port 132.

For moving plunger 108, the end of casing 106 has a nut 133 with a through passage 134. Nut 133 clamps a bushing 135, the end of which forms a valve seat engaged by the end of plunger 108. Passage 134 is connected by a branch conduit 136 to conduit 138 which connects with inlet port 114. Branch conduit 136 has an adjustable throttle valve 140 which can provide a restriction greater than any restriction from conduit 138 to chamber 63. When the desired pressure is developed in chamber 63, the pressure in passage 134 acting on the end of plunger 108 moves the plunger against the action of spring 110 to connect port 120 to inlet port 114 for procuring opening of valve 66 for starting the unit.

A small bleed passage 140 in casing 106 provides fluid connection from the end of plunger 108 to groove 130 which connects with vent port 132. This permits gas leaking past the end of plunger 108 to be vented so that the plunger will not be moved from the position shown until the desired pressure has been built up in chamber 63.

A passage 144 in casing 86 connects passage 99 with groove 103 in cap 92 and is closed by a check valve 146. After the starting unit has operated and conduit 122 is vented by plunger 108 returning to the position shown, gas at the right of piston 76 in cylinder 74 may escape past valve 146 so that piston 76 may move into a position for closing poppet valve 66.

The piston assemblies may be automatically moved to the outer ends of their stroke before the starting devices operate. The structure is the same for each piston assembly and only one of the structures will be described. Compressor piston 18 has projecting concentric sleeves 148 and 149, Fig. 4, connected at their outer ends to form a plunger 150 sliding in an annular space 151 between a sleeve 152 and a smaller sleeve 153 mounted within the unit. Only one plunger is shown, but for purposes of balance, two oppositely placed plungers may be advantageous.

Gas under pressure is admitted by a supply valve 153 to the left hand end of space 151 to move the piston assembly of which piston 18 is a part. The supply valve casing 154 has a sliding plunger valve 156 held in the position shown by a spring 158. In this position gas entering an inlet port 160 passes around a groove 162 in valve 156 to an outlet port 164 connected by a conduit 166 to the end of a bore 168 in a casing 170 at the end of sleeve 152. From bore 168 gas under pressure passes through a channel 172 in casing 170 and a channel 174 in head 175 on sleeves 152 and 153 to the inner end of space 151. Gas entering the end of this cylinder moves plunger 150 to the right, carrying with it the attached piston assembly and moving the piston assembly into starting position.

As plunger 150 moves to the right, it uncovers a port 176 connected by a conduit 178 to a passage 180 in a cap 181 in the end of casing 154. Gas entering this passage acts on the end of valve plunger 156 which is in the form of a valve engaging a seat 182 in a ring 183 at the end of passage 180 and moves the plunger to the left against the force of spring 158. Inlet port 160 is then connected by groove 162 to a port 184 which is connected by conduit 186 to the starting 75 release valve.

When valve plunger 156 is moved to the left, port 164 is connected by a groove 186 in plunger 156 to a vent port 188 causing a pressure drop in conduit 166 and permitting a check valve in the form of a plunger 190 in bore 168 to be moved by a spring 192 to close passage 172.

After the engine is started, plunger 150 acts as a pump forcing gas under pressure through passage 174 past a disc valve 194 and through a channel 196 to a conduit 198 leading to the left hand end of casing 154. Pressure entering the casing acts on the end of valve plunger 156 to return it to the position shown. While gas under pressure is being admitted to the balance pump, valve 190 is moved into a position to close passage 196. This passage is opened upon return of valve 190 to the normal position shown.

The starting system above described is claimed in the copending application of Cooper, Serial No. 550,875, now Patent No. 2,439,453 of April 13, 1948. The present invention relates to the arrangement by which any one of the number of units in the power plant may be started selectively by a starting system of this character.

Referring to Fig. 4, the supply of starting gas may be controlled by a valve 200. This valve may include a casing 202 having a slide valve 204 moved in a direction to cut off fluid connection between an inlet port 206 and an outlet port 208 by a spring 210. Port 208 is connected by a conduit 212 to the port 160 of the supply valve. The plunger 204 is moved in a direction to provide fluid connection through the valve by a solenoid 214. Port 206 is connected to a main conduit 216 leading to a supply of gas under pressure which may be, for example, a tank of compressed air or gas, or a cartridge discharging device. Conduit 216 has a manually controlled valve 218 which is located at the control station for the power plant.

As shown in Fig. 5 there is a control valve 200 for each of the several generators in the power plant and each control valve is adapted to admit the compressed gas to the above described starting system for the generator with which the control valve is associated. An electrical selector 220 located at the control station and having a manually movable indicator 222 adapted to complete a circuit through a source of power represented by a battery 224 and any one of the control valves 200 selectively dependent upon the location of the indicator 222. As shown, contacts 226 engageable by the indicator 222 are connected to the solenoids of the control valves and the other terminal of each of the solenoids is grounded at 228. The indicator 222 is connected through the source of power to a ground 230 to complete the circuit through the individual control valves.

In starting the power plant, the operator, by adjustment of the indicator 222, selects which of the units he wishes to start and by completing the circuit through the solenoid of the selective control valve establishes fluid connection from conduit 216 to the supply valve of the selective unit. By opening valve 218 the starting system for the selected unit is then set in operation and continues to operate until the selected unit is running. This procedure is repeated for each of

the units until all of the units are running. If any unit stalls, the arrangement described permits the operator to set in operation the starting system for the stalled unit without affecting the remaining units. The use of an electrical selector system permits the elimination of all pneumatic or fluid circuits from the control station to the power plant, the only line necessary being the main supply conduit 216.

It is to be understood that the invention is not limited to the specific embodiment herein illustrated and described, but may be used in other ways without departure from its spirit as defined by the following claims.

I claim:

1. A control system including a number of free piston units and a starting mechanism for each unit, including a pressure operated starting device and an automatic supply valve for said device, said system also including a conduit having a supply of starting gas, a branch conduit from said supply conduit to each supply valve and a normally closed control valve in each branch conduit, in combination with a selector including a manually movable indicator for selecting which unit is to be started, and an electrical circuit for each control valve, said indicator having associated therewith contact means for completing any of the electrical circuits selectively and electrical means associated with each control valve for operating said valve when the associated circuit is completed.

2. A control system including a number of free piston units and a starting mechanism for each unit, including a pressure operated starting device and an automatic supply valve for said device, said system also including a conduit having a supply of starting gas, a branch conduit from said supply conduit to each supply valve and a normally closed control valve in each branch conduit, in combination with a single electrical control means including a number of parallel electrical circuits with one circuit for each control valve, electrically actuated means associated with each control valve and included in the associated circuit for actuating said valve, and a selector switch for completing each of said circuits selectively, said switch being manually actuated for the purpose of selecting which of the free piston units is to be started.

DONALD E. MEITZLER.
